UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

SMALL BANK.

1,369,675.

Specification of Letters Patent. Patented Feb. 22, 1921.

Application filed February 23, 1918. Serial No. 218,623.

To all whom it may concern:

Be it known that I, ISIDOR J. KUSEL, a citizen of the United States, residing at Chicago, in the county of Cook and State of Illinois, have invented a certain new and useful Improvement in Small Banks, of which the following is a full, clear, concise, and exact description, reference being had to the accompanying drawings, forming a part of this specification.

My invention relates to small banks, particularly for use with coins, although of course they may be used for other purposes.

One of the objects of my present invention is to provide a simple, practical and advantageous construction of small bank.

Another object of the invention is to make the bank of an attractive form and appearance.

Another object of the invention is to make a bank of such form and appearance that its use as a bank will not be suspected.

Another object of the invention is to arrange for the use of a hat-shaped article as a bank.

Another object of the invention is to provide an article which will serve not only as a small bank, but also as a novelty for advertising or similar purposes.

In accordance with my invention I employ a hat-shaped article and arrange it for use as a bank. The chamber or space forming the interior of the crown of the hat I utilize as a space for coins, bills, or the like, and I provide a closure for this space so that the contents will be maintained therein. This closure is preferably made removable in whole or in part so that it may serve to maintain the coins, bills and the like inside of the bank, and furthermore may be removed so as to allow such articles to be removed. A suitable slot or opening for the admission of coins, bills, etc., may be provided, as for example in the removable closure forming the closure for the chamber in the hat crown.

In the accompanying drawings Figure 1 is a perspective view of a hat-shaped article such for example as a soldier's hat, embodying my present invention;

Fig. 2 is a view of the under side of the same looking upwardly;

Fig. 3 is a vertical section taken on line 3—3 in Fig. 2 on an enlarged scale;

Figs. 4 and 5 are views of details of construction.

Referring to the drawings, I show a hat-shaped article A, preferably in the form of a soldier's hat having a crown 1, a brim 2. A closure 3 is provided to close the space inside of the crown 1 and thus make a space or chamber 4 in which the coins and bills, etc., may be placed. This closure 3 is preferably made removable to permit the coins, bills, etc., to be taken out and also provided with suitable locking means by which it may be temporarily locked in place. To such end the closure 3 is made with a rim or flange 4 which fits snugly within the lower portion of the crown 1. This fit is so snug that the closure or bottom 3 will snap into place when pushed in, the flange 4 being preferably provided with an annular groove 5 and the crown 1 with a series of small projections 6 adapted to fit into the groove 5. The closure or bottom 3 is preferably arranged to be substantially in alignment with the flat under surface of the brim 2.

While the slot for the coins, bills, etc., could be in different places, I prefer to locate said slot in the floor or closure 3, such a slot 7 being shown in the same. This slot 7 is of sufficient size to take any desired coin or even any coin or bill, and is preferably provided with a spring 8 having a slot 9, this spring being for the purpose of permitting the coin or bill to enter the bank but preventing its escape from the same. This spring 8 may be secured in position by means of an eyelet or rivet 10 with side flanges 11 to hold the spring against sidewise movement. Thus a complete bank is formed which will be secure and effective as a small bank and may also be used as an advertising novelty or something of that sort. The appearance of the article will not betray the fact that it is a bank if it is desired to use it as a novelty or a paper weight or something of that sort.

As a means for removing the closure 3 I may use a key or opener 12 having a shank 13 adapted to fit into the opening or slot 7 and also having a prong 14 capable of extending to the brim 2. Thus by prying or pushing downwardly on the key 12 the closure 3 may be worked or pried loose and removed from the crown 1, the bank thereby

being open to permit the removal of its contents. It may be again closed by simply pushing and snapping the closure 3 into place.

5. It will be understood that changes and modifications may be made without departing from the spirit of the invention.

What I claim is:

10. A small bank comprising a hat-shaped article having a removable closure provided

with means whereby it may be temporarily locked in position, said means comprising an annular rim on the closure, said rim being provided with an annular groove and projections on the interior of the crown 15 adapted to fit into said annular groove.

In witness whereof I hereunto subscribe my name this 16th day of February, A. D. 1918.

ISIDOR J. KUSEL.
